United States Patent Office.

WILLIAM WHARTON, JR., OF PHILADELPHIA, PENNSYLVANIA.

Letters Patent No. 74,461, dated February 11, 1868.

IMPROVED RAILWAY FROG.

The Schedule referred to in these Letters Patent and making part of the same.

TO ALL WHOM IT MAY CONCERN:

Be it known that I, WILLIAM WHARTON, Jr., of Philadelphia, Pennsylvania, have invented an Improvement in Railroad Frogs; and I do hereby declare the following to be a full, clear, and exact description of the same, reference being had to the accompanying drawing, and to the letters of reference marked thereon.

My invention relates to an improvement in the railroad-frog for which Letters Patent were granted to me on the 18th of July, 1865, and my improvement consists in the manner, substantially as described hereafter, of securing, by bolts or other equivalent fastenings, the main rail to the frog, so that the former can be removed from the latter more readily than from the frog described in my aforesaid patent.

In order to enable others skilled in the art to make and use my invention, I will now proceed to describe its construction and operation. On reference to the accompanying drawing, which forms a part of this specification—

Figure 1 represents my improved frog with adjacent rails.

Figure 2, a transverse section on the line 1-2, fig. 1.

Figures 3 and 4, modifications of the frog.

Figure 5, a transverse section on the line 3-4, fig. 4; and

Figure 6, another modification of the frog.

On reference to fig. 1, A and A' represent the rails of the main track, and B and B' those of the turn-out, D being the frog, situated at the crossing of the rails A' and B. This frog is a substantial casting, made, in the present instance, of one piece, and secured to the track by bolts or spikes passing through lugs *aa*. It will be observed that the continuity of the rail B of the turn-out is interrupted for the reception of the frog, while the latter has a recess, *b*, for the reception of the rail A' of the main track, so that the continuity of the latter is uninterrupted. In these respects the frog is similar to that described in my patent of July 18, 1865, in which frog, however, the rail fitted so closely and tightly to the recess of the frog that its removal was a matter of difficulty. In the present improvement, the recess *b* is at its narrowest point considerably wider than the rail, to which one side only of the said recess is adapted, as best observed on reference to fig. 2, the rail being secured to that side of the recess adapted to it by bolts *e*. On removing the nuts of these bolts, the rail can be moved laterally, and after this, readily withdrawn longitudinally. The rail B of the turn-out is elevated above the level of the rail A' of the main track, the rib *d* of the frog, where it meets the said rail, having a corresponding elevation, so that the flanges of the car-wheels, as they traverse the turn-out in the direction of the arrow and across the frog, may be elevated above the main rail A', as described in my aforesaid patent.

In fig. 3, the frog is similar to that illustrated in fig. 1, with the exception that in the former figure a portion, *y*, of the frog forms a part of the main rail A', and renders the same continuous.

In the modification illustrated in figs. 4 and 5, the frog is made of two parts bolted together, so as to embrace and confine the main rail in a manner which will be readily understood without description.

In the modification, fig. 6, the frog is also in two parts bolted together, so as to confine the rail. In this case, however, a portion, *y*, of one part of the frog forms a continuation of the said main rail.

I claim as my invention, and desire to secure by Letters Patent, as an improvement in the frog described in my patent of July 18, 1865—

The frog *D*, having a shoulder against which the side of the main rail bears, and to which it is confined by bolts *e*, or their equivalents, substantially as and for the purpose described.

In testimony whereof, I have signed my name to this specification in the presence of two subscribing witnesses.

W.M. WHARTON, JR.
